UNITED STATES PATENT OFFICE.

RAYMOND R. FUDGE, OF FORT WORTH, TEXAS.

INDICATING DEVICE FOR AUTOMOBILE RADIATORS.

Application filed September 23, 1922. Serial No. 590,102.

To all whom it may concern:

Be it known that I, RAYMOND R. FUDGE, a citizen of the United States, residing at Fort Worth, in the county of Tarrant and State of Texas, have invented certain new and useful Improvements in Indicating Devices for Automobile Radiators, of which the following is a specification.

The invention relates to certain new and useful improvements in temperature indicators and pertains more especially to indicators for registering the temperature of the water of automobile radiators.

The primary object of the invention is to provide an indicator which is visible to and can accordingly be easily read by the driver at night and one wherein atmospheric temperature is prevented from exerting its influence upon and thus destroying the accuracy of the indicating media in correctly registering the water temperature.

The invention further aims to utilize the reflection of the headlight rays in enabling night reading by the driver.

The invention has further and other objects which will be later set forth and manifested in the course of the following description.

In the drawings:

Figure 1, is a rear side elevation, the radiator cap being broken away and shown partly in section;

Figure 2, is a similar view, parts being omitted;

Figure 3, is a fragmentary vertical sectional view, partly in side elevation;

Figure 4, is a section on line 4—4 of Figure 1, and

Figure 5, is a section on line 5—5 of Figure 3.

In proceeding in accordance with the present invention, the radiator cap is designated 1, and is mounted on the tubular shank 20 of a stem having a head 10, the shank being perforated at A and having a threaded lower end. A sleeve or jacket 3 surrounds the stem in spaced relation thereto and forms a water space in conjunction therewith, the sleeve at its upper end engaging the cap 1 and at its lower end is engaged by a nut 11 threaded on the lower end of the shank. The sleeve 3 is thus held rigidly onto the stem and the cap 1 in turn rigidly held against the head 10 of the stem, where by all of the recited parts are secured in their assembled relation by the nut 11.

The upper end of the sleeve has an upwardly facing conical water collecting cup secured thereto, which conveys the water through openings A' formed in sleeve 3 into the water space formed by the shank 20 and sleeve or jacket 3. A portion of the water and vapors arising to the surface of the radiator cap from the heated radiator and due to boiling and churning of the water permits water and vapor to collect in the water collecting cup 2 and it passes thence through perforations A—A to space surrounding mercury tube 6. Below the cup 2, a series of downwardly facing conical heat radiating fins 4 are secured to the sleeve 3.

The mercury tube 6 has mercury 5 therein and is arranged to project into the shank 20 and into the dial 13, the latter having a blue colored area 7, to designate cool water; a red colored area 9 to designate danger or overheating of the water and a plain colored area 8 with suitable indicia, as "O. K." to designate normal condition of the water.

For the purpose of enabling reading of the temperature at night, the reflection of the light rays of the automobile headlight is utilized in conjunction with a pair of mirrors 12 the latter disposed at approximately right angles to each other and with their adjacent sides spaced and arranged with the mercury tube 6 in such space to allow the driver of the car to view the tube and read same.

The heat radiating fins function to maintain uniform temperature between the water in the radiator and that within the water jacket.

What is claimed is:

1. An auto radiator temperature indicator including a dial having an upper danger indicating area, a lower subnormal indicating area and an intermediate normal indicating area, a mercury tube carried by the dial and projecting therebelow, a perforated tubular stem surrounding the projecting end of the tube, a sleeve surrounding the stem and spaced therefrom to form a water space in conjunction therewith, a water collecting cup secured to the sleeve adjacent the top thereof, the sleeve having perforations to conduct the water entering the cup into the water space, and heat radiating fins carried by the sleeve and disposed below the cup.

2. An auto radiator temperature indicator including a dial having an upper danger indicating area, a lower subnormal indicating area and an intermediate normal indicating area.

cating area, a mercury tube carried by the dial and projecting therebelow, a perforated tubular stem surrounding the projecting end of the tube, a sleeve surrounding the stem and spaced therefrom to form a water space in conjunction therewith, a water collecting cup secured to the sleeve adjacent the top thereof, the sleeve having perforations to conduct the water entering the cup into the water space, heat radiating fins on the sleeve

below the cup, and head on the stem, a radiator cap on the stem engaged with the head, the upper end of the sleeve engaging the cap to force same against the head, and a nut threaded on the stem and engaging the lower end of the sleeve.

In testimony whereof I have signed my name to this specification.

RAYMOND R. FUDGE.
